UNITED STATES PATENT OFFICE.

MAURICE GOLDBERGER, OF CHICAGO, ILLINOIS.

FILLING AND CAPPING MACHINE.

Application filed April 17, 1925. Serial No. 23,824.

This invention relates to improvements in filling and capping machines particularly adapted though not necessarily limited in its use, for filling and capping milk bottles, 5 and one of the objects of the invention is to provide an improved machine of this character in which there is provided means adapted to feed the bottles to the filling and capping mechanism, and from which machine the bottles may be freely removed from any position 10 during the operation of the machine, particularly during the filling of the bottles.

A further object is to provide in a machine of this character improved spider like feeding and receiving elements, the feeding element to centralize the bottle accurately with respect to the filling and capping mechanism, the removing element extending for a considerable distance around the bottle and 20 operating to hold the bottle during the filling and capping operations, both of the said elements being freely removable and interchangeable with other like elements adapted for feeding and centralizing bottles of varying 25 diameters and capacities.

A further object is to provide in a machine of this character continuously traveling conveyors and intermittently operating bottle handling elements, one of which elements 30 operates upon the empty bottles to feed and centralize them with respect to the filling and capping mechanism, and the other of which elements removes the filled and capped bottles and delivers them to one of the conveyors 35 to be conveyed away, and improved means for intermittently and successively removing the empty bottles from one of the conveyors and placing them in a position to be engaged by one of the bottle handling elements, the said removing means also operating 40 as a stop to arrest the advancing movement of the empty bottles on the supply conveyor, the said removing element operating to place the filled and capped bottles upon 45 one of the conveyors.

A further object is to provide an improved machine of this character which will be of a comparatively simple construction with a compact arrangement of parts, and in which 50 machine the filling, capping and removal of the bottles from the machine will take place at substantially the same point in the machine, the capping taking place at the next step in the intermittent advancement of the 55 bottle after being filled, thereby reducing to a minimum the possibility of any foreign

matter entering the bottle between the filling and capping stations in the machine.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a top plan view of an improved machine of this character constructed in accordance with the principles of this invention, and as taken on line 1—1, Figure 2, and with parts omitted.

Figure 2 is a sectional view as taken on line 2—2, Figure 4.

Figure 3 is a side elevation of the machine 75 taken from the right hand side of Figure 1, and with parts in section.

Figure 4 is a sectional view taken on line 4—4, Figure 2.

Figure 5 is an enlarged detail top plan 80 view, with parts in section and parts broken away, of the conveyors and the feeding and removal elements for the bottles.

Figure 6 is a sectional view taken on line 6—6, Figure 2.

Figure 7 is a detail top plan view of one of the bottle feeding elements for handling bottles of a smaller size.

Figures 8 and 9 are top plan views of bottle handling elements for handling bottles of 90 one size.

Figures 10 and 11 are views similar to Figures 8 and 9 respectively of the bottle handling elements for handling bottles of a different size.

Referring more particularly to the drawings the numeral 15 designates generally a base preferably supported for some distance above the floor by means of a suitable support 16. An upright 17 is mounted upon the base in a suitable bearing and projects for a suitable distance above the base and is held against rotation with respect to the base in any suitable manner. A supporting member 18 is rotatably mounted upon the base 15, 105 preferably through the medium of the upright 17, about which the member 18 is rotatable, and the member 18 is preferably supported by means of a suitable thrust bearing 19 which is supported by the end of the 110 bearing 20 in which the upright 17 is mounted. The member 18 is preferably held

against displacement with respect to the upright 17 by means of a cap or member 21 recessed into the upper face of the member 18 so as to abut the end of the upright 17, 5 and a fastening device 22 such as a bolt or the like passes through the element 21 and into the end of the upright 17.

The member 18 may be of any desired configuration, but is shaped to form a shield for 10 the mechanism disposed therebelow and is preferably inclined downwardly from its axis toward the periphery thereof.

Mounted upon the member 18 and projecting thereabove is a container 23 for holding 15 the milk or other liquid with which the bottles are to be filled, and which liquid is dispensed through suitable filling mechanism 24.

The container 23 is adjustably supported upon the member 18 in any suitable manner, 20 preferably through the medium of telescoping members 25-26, the member 25 being mounted upon the member 18 and the member 26 being connected with the bottom of the container 23. The member 25 is provided 25 with a bearing 27 interior thereof in which a shaft 28 is rotatably mounted, one end of the shaft 29 is threaded and engages into a threaded portion 30 of the member 26. A gear 31 is connected with the shaft 28 and this 30 gear meshes with another gear 32 carried by a shaft 33. The ends of the shaft 33 are preferably shaped as at 34 to receive a crank, by means of which the shaft 33 may be rotated. When this shaft is rotated the threaded end 35 29 of the shaft 28 co-operating with the threaded portion 30 of the member 26, will cause the members 25 and 26 to be relatively adjusted so as to raise or lower the container 23 with respect to the member 18. A slot 40 35 may be provided in the member 26 and a pin or bolt 36 may be connected with the member 25 to move in the slot 35 so as to maintain the members 25 and 26 in proper relative position and to guide them in their relative 45 movement.

The end of the member 26 may be split as at 37 and a clamping bolt or element 38 may be provided for clamping the end of the member 26 about the member 25 to retain the parts 50 in their relative adjusted positions. The member 25 may be provided with graduations or indications 39 with which a portion 40 of the member 26 co-operates for indicating the adjustments necessary to compensate the different sizes of bottles to be filled.

The member 18 is adapted to be intermittently rotated in any desired or suitable manner but preferably through the medium of a Geneva movement, one of the Geneva members 41 of which is secured in any suitable manner to the member 18 beneath the top thereof, the other Geneva member 42 which co-operates therewith, being secured to an upright shaft 43 journaled in a suitable bearing 44 carried by the base 15. This shaft 43

projects for any desired distance beneath the base 15 and has secured to it a gear 45, preferably of the spiral type. With this gear 45 another gear 46 meshes and this gear 46 is connected with a shaft 47 which extends 70 across and beneath the base and is mounted in suitable bearings. The shaft 47 receives its motion from a suitable source such as a motor 48 mounted upon the base and which motor is connected preferably through the 75 medium of intermediate gearing 49 with a gear 50 which is secured to the shaft 47 so that when the shaft 47 is rotated an intermittent rotation will be imparted to the member 18 through the medium of the geneva 42-41. so

Carried by the member 18 are a plurality of bottle supports 51 for receiving the bottles and presenting them to the filling and capping mechanism, any number of which supports may be employed, and as the construction and operation of each of these supports is the same, the description of one will apply to them all. The support embodies a platform upon which the bottle rests and this platform is preferably elongated so that the 90 bottle may be properly positioned thereon and moved therewith and with respect thereto. An upright 52 projects below the platform and is movable in a suitable guide or bearing 53 carried by the member 18. An 95 upright 54 is connected with the upright 52 preferably through the medium of a shoulder 55 through which one extremity of the upright 52 passes. The lower end of the upright 52 is preferably reduced in diameter 100 to form a shoulder 56 which co-operates with the shoulder 55 and against which shoulders the respective ends of an elastic member 57, such as a coil spring, rest, the spring extending into the bearing and forms a cushion for the bottle while the latter is being presented to the filling mechanism.

Connected with the upright 54 is a roller 58 which is adapted to travel upon a track 59 of a cam shaped formation so that when the member 18 is rotated the roller 58 will traverse the track 59 and the bottle support 51 will be raised and lowered according to the portion of the track upon which the roller 58 is traveled. The track is supported by 115 the base 15 and may be secured thereto and by means of suitable fastening devices 60.

If desired a member 61 may be provided along predetermined portions of the track 59 beneath which a projecting extremity 62 of the axle of the roller 58 passes, and said member 61 serves as a means for positively drawing down or lowering the bottle support 51.

The bottles to be filled and capped may be supplied to the machine from any suitable source such as from a washing machine designated generally by the reference numeral 63, and are delivered onto a continually traveling conveyor 64 of any suitable construction, and from which conveyor the bottles are 130

adapted to be removed at a point in proximity to the path of rotation of the bottle supports 51. Another continuously traveling conveyor 65 is provided for receiving the filled and 5 capped bottles and for conveying them away. The conveyors 64 and 65 are preferably arranged to travel in directions transverse to each other, and between the conveyors and the rotatable bottle supports 51 are arranged the 10 bottle feeding and bottle removing mechanism. A supporting member or table 66 is provided for receiving the bottles from the conveyor 64, and from which support 66 the bottles are removed to the conveyor 65. The 15 surface of the support 66 is flush with the tops of the conveyors 64 and 65 and also flush with the tops of the bottle supports 51 when the latter are in their lowermost positions.

A rotatable spider like element 67 is provided for receiving the bottles from the conveyor 64 and delivering them to the bottle supports 51. This element 67 is provided with a series of arms or portions 68 which are of a semicircular configuration, and the member 67 is removably connected with an upright shaft 69 journaled in suitable bearings preferably in the supporting member or table 66 and the base 15. The member is removably secured to the shaft 69 preferably by means 20 of a pin or projection 70 which projects into an aperture 71 in the member 67. The shaft 69 is so disposed with respect to the bottle supports 51 that when the bottle supports are lowered and the shaft 69 is rotated in the direction indicated by the arrow in Figure 1, the arms or portions 68 will pass over the bottle supports 51 to move the bottles from the supporting surface or table 66 on to the bottle supports 51. A guard 72 is provided adjacent 25 the path of movement of the arms 68 so as to prevent the bottle from being displaced when the member 67 is rotated and one of the arms 68 contacts with the bottle.

The bottles are ejected from the conveyor 45 64 preferably by means of a reciprocating arm 73 which is pivotally supported as at 74 upon a slide 75. One extremity of the arm 73 is deflected as at 76 and serves as a stop for arresting the bottles as they are advanced by 50 the conveyor 64 and without interfering with the traveling movement of the conveyor 64. The other extremity of the arm 73 is provided with a projection 77 which co-operates with a stop 78, and an arm 79 is also connected with 55 the arm 73 to project beyond the other side of the pivot 74. A spring 80 is adjustably connected by one extremity to the arm 79 and is anchored by its other extremity to the slide 75, the latter being adapted to be reciprocated upon the guide 81.

In the normal position, the arm 73 assumes the position shown in Figure 1, that is to one side of the conveyor 64. When the bottle assumes a position on the conveyor to be engaged by the arm 73 when the latter is moved

forwardly to eject the bottle on to the table or support 66 the end 76 of the arm will move into the path of the advancing movement of the bottles on the conveyor 64 and arrest their movement while the movement of the conveyor 70 or will not be interfered with.

The tension of the spring 80 on the arm 79 is such that the arm 73 may be moved forwardly under normal conditions to eject one of the bottles from the conveyor 64 but in the event of any abnormal condition such as the bottles becoming jammed, the arm 73 will yield and will turn about the pivot 74.

Any suitable means may be provided for reciprocating the arm 73 and the slide 75 such as an arm 82 connected at one end to a rock shaft 83 journaled in suitable bearings 84. The arm 82 is provided with a slot 85 for receiving a pin or lug 86 on the slide 75. An arm 87 is also connected with the rock shaft 83 and a link 88 is connected by one end as at 89 with the arm 87 and by the other end to a crank 90, and which crank 90 is connected with the shaft 47 for rotation therewith. Thus it will be seen that when the shaft 47 90 is rotated the shaft 83 will be rocked and the slide 75 will be given a forward and backward reciprocating movement.

When the bottle is engaged by the arm 73 and is ejected from the conveyor 64 it will be 95 moved upon the table or support 66 (see Figure 1) and in a position to be engaged by the advancing arm 68 of the member 67. The arms 68 being semi-circular in shape are constructed on a radius to receive the bottle and to extend partially therearound. As the arm 68 advances it will engage the bottle and the guard 72 co-operating with the arm will cause the bottle to be properly positioned with respect to the arm so that when the arm moves 100 the bottle off of the table or platform 66 on to the bottle support 51, the bottle will be centralized with respect to the filling mechanism.

The member 67 is adapted to be intermittently rotated and operates in timed relation 110 with the rotation of the bottle supports 51.

Motion is imparted to the shaft 69 from the shaft 47 (see particularly Figure 4) through the worm or spiral gears 46-45, 115 shaft 43 and gear 91 (see also Figures 2 and 3) which is carried by the shaft 43. This gear 91 meshes with a gear 92 carried by a shaft 93 (see also Figure 6) to which shaft is connected an arm 94 forming one of the elements of a Geneva movement. The other 120 element 95 of the geneva is connected with a shaft 96 which is journaled in a suitable bearing 97 on the base 15 and a bearing 98 carried by a bracket 99 which is disposed beneath the base 15 and in which bracket 99 125 the shaft 43 is journaled.

Connected also with the shaft 96 for rotation with the Geneva element 95 is a gear 100, which gear in turn meshes with a gear 101 connected with a shaft 102 for rotation there- 130

with. The shaft 102 is journaled in suitable bearings in the base 15 and in the supporting member or table 66. The gear 101 in turn meshes with a gear 103, connected with the shaft 69.

Thus it will be seen that the shaft 69 carrying the element 67 will be given an intermittent rotation, and as the Geneva element 95 is a four-step movement, four steps of movement will be given to the shaft 69 and member 67 on each complete rotation of the shaft 69, and a similar motion will be given to the shaft 102.

The geneva comprising the elements 41 15 and 42 which control the intermittent rotation of the member 18 and the bottle supports 51 having an eight-step movement, the member 18 will be given eight steps of movement during one complete revolution thereof.

20 The member 18 and the bottle supports 51 are intermittently rotated in the direction indicated by the arrow in Figure 1, while the shafts 69 and 102 with the bottle handling mechanism thereon, are given intermittent 25 steps of rotation in directions in opposition to each other, and as indicated by the arrows in Figure 1.

30 Removably connected with the shaft 102 is a bottle handling or removing element 104, similar to the element 67, and is provided with arms 105 of a semi-circular configuration adapted to pass over the bottle supports 51 when the shaft 102 is rotated to engage the bottles and move the filled bottles from the support 51 onto the table or support 66 in a 35 position to receive the caps.

40 The arms 105 being of a semi-circular configuration, extend for a considerable distance about the bottle and operate as a means for holding the bottle while it is being capped. The element 104 is removably secured to the shaft 102 in a manner similar to the manner in which the element 67 is secured to the shaft 69, that is through the medium of a 45 pin 70 carried by a collar secured to the shaft 102 for rotation therewith.

50 The element 18 is intermittently rotated in the direction indicated by the arrow thereon in Figure 1, and the elements 67 and 104 are also intermittently rotated in opposite directions with respect to each other and also with respect to the intermittent rotation of the element 18 and bottle supports 51, so that during the intermittent movement of the element 18 and bottle supports 51, the elements 67 and 104 will remain at rest, and during the intermittent rotation of the elements 67 and 104 the element 18 and bottle supports 51 will remain at rest. The elements 67 and 104 rotate in unison and in opposition to each other, the element 67 operating to place the empty bottle upon the adjacent bottle support 51 and to centralize it thereon, while the element 104 removes the 60 filled bottle from the adjacent bottle support 65

51 and places the same in position to receive a cap during one step of intermittent rotation of the element 104. Upon the next step of rotation of this element the filled and capped bottle is shifted from the capping station and delivered to the conveyor 65 to be 70 conveyed away.

It will be noted that during the capping of the bottle one of the arms 105 remains in contact therewith and serves as a means for 75 assisting in holding the bottle while it is being capped.

The capping mechanism may be of any desired and suitable construction designated generally by the reference numeral 106 (see 80 particularly Figure 3) and is adapted to be vertically reciprocated so as to move the same into an operative position with respect to the bottle when the latter is placed thereunder and to elevate the mechanism to permit the 85 removal of the bottle. This may be accomplished preferably by means of a member 107 in the form of an upright which moves in a suitable guide or bearing 108 (see particularly Figures 3 and 4) and the member 107 is 90 adapted to be reciprocated by means of a suitable link 109 which is connected with the member 107 and also with a crank 110 secured to a shaft 111, journaled in suitable bearings beneath the base 15, and which shaft 111 receives its motion through the medium of a gear 112, preferably of the bevel type, secured to the shaft 111, and which gear meshes with a similar gear 113 secured to the shaft 47 for 95 rotation therewith. Obviously the connections between the reciprocating member 107 of the capping mechanism and the shaft 47, is such that it will operate the capping mechanism in timed relation with respect to the placing and removal of the filled bottle with 100 respect to the capping mechanism.

105 In order to compensate for varying sizes or heights of bottles, the capping mechanism 106 is adjustably mounted upon the reciprocating member 107 so as to be vertically adjusted 110 with respect thereto. This may be accomplished by means of a collar 114 which encompasses the member 107 and which collar carries a gear or pinion 115, which meshes with a rack or teeth 116 on the member 107, the gear or pinion being rotatable preferably through the medium of a handle 117. Indications 118 may be provided on the member 107 with 115 which a portion of the collar 114 may co-operate so as to indicate the extent of adjustment 120 of the capping mechanism. Any suitable means may be provided for locking or securing the capping mechanism in its adjusted position with respect to the member 107, such as a binding screw or member 119.

125 When the filled bottle is removed from the bottle support 51 and into a position to be operated upon by the capping mechanism, the bottle will be moved and positioned upon a yieldable support 120, preferably em-

bodying a platform depending beneath which is a stem 121 which passes through a suitable guide 122 supported by any portion of the mechanism, preferably the support or table 5 66. The lower end of the stem 121 is preferably threaded as at 123 to receive nuts or collars 124 and a coiled spring 125 encompasses the stem 121 above the guide 122, one end of the spring engaging the guide and the other 10 end engaging the bottom of the platform or support 120. The spring 125 serves as a cushioning device for the bottle when being operated upon by the capping mechanism, thereby resiliently supporting the bottle and 15 the resilient element is centrally disposed beneath the bottle and also serves to compensate variations in the heights of the bottles or capacities, and prevents breaking of the bottle by the capping mechanism. Obviously a 20 stronger or weaker cushioning element 125 may be provided when desired.

As soon as the capping mechanism is raised to release the bottle the element 104 will remove the filled and capped bottle from the 25 platform or support 120 and will place it upon the conveyor 65.

Motion is imparted to the conveyors from any suitable source, not shown.

The bottle inserting and removing elements 30 67 and 104 as shown are of a similar size, that is they are adapted to handle bottles of one size and of the largest capacity. When, however, it is desired to handle bottles of a different size the elements 67 and 104 may be readily 35 removed by lifting them from their respective shafts, and other elements such as the elements 126 and 127 respectively interchanged therefor. The respective arms 128—129 of these elements 126—127 are of a semi-circular 40 shape but the diameter of the bottle engaging portions thereof are of a size to permit a smaller bottle to be engaged thereby so that while the element 126 is placing the bottle in position upon the bottle support 51, they will 45 centralize the bottle with respect to the filling mechanism, and while the element 127 is shifting the bottle from the filling station to the capping station it will encompass the bottle and hold it while being capped and then 50 remove the same to the conveyor 65.

The arm 73 (see particularly Figures 1 and 5) which operates as an ejector for removing the empty bottles from the conveyor 64 and placing them in a position to be engaged by 55 the respective receiving elements 67 or 126, and which arm also arrests the advancing movement of the bottles on the conveyor 64, is of such a size and construction that it will handle bottles of different size and capacities 60 without necessitating the separate adjustment of the arm 73 or the interchanging thereof with another arm. This is accomplished by reason of the fact that the distance between the end of the arm 73 and a stop 130 (see Figures 1, 5 and 7) arranged to arrest the for-

ward movement of the empty bottles on the conveyor before being operated upon by the arm 73, is of a length to remove from the conveyor 64 bottles of the smallest diameter.

If desired and when smaller bottles are 70 being fed upon the conveyor 64 (see particularly Figure 7) a suitable guide 131 may be adjustably secured along one side of the conveyor 64 by means of suitable adjusting devices 132. This guide 131 may be positioned 75 to extend over a portion of the conveyor 64 so as to cause the empty bottles 133 of the smaller size to be maintained in alignment upon the conveyor 64 and while being advanced thereby.

It is thought that the operation of this apparatus will be clearly understood from the foregoing description, but briefly stated it is as follows (particular reference being had to Figures 1, 2 and 3).

The empty bottles are fed in any suitable manner from the washing machine 63 onto the conveyor 64, and which conveyor 64 together with the conveyor 65 are continually moving. The bottles are advanced by the 90 conveyor 64 until the foremost bottle engages the stop 130, at which time the conveyor 64 will continue to move while the motion of the bottles will be arrested. The arm 73 is then operated to move the foremost bottle 95 from the conveyor 64 onto the support or table 66 and in a position that it will be engaged by the adjacent arm 68 of the intermittently rotating element 67. The element 67 moves in the direction indicated by the arrow 100 and will eventually place and centralize one of the bottles upon the adjacent bottle support 51 while the latter, together with the element 18, is at rest. The elements 67 and 104, the latter being provided to remove the filled bottle from the bottle support 51, are intermittently rotated in unison and in opposite directions.

After the bottle has been placed upon the support 51 the elements 67 and 104 will have 110 completed one step of rotation and will then be at rest. While the arm 73 is ejecting the bottle from the conveyor 64, the portion 76 of the arm will serve as a stop for the next adjacent bottle. The arm 73 is then moved back to the position shown in Figure 1 to permit the bottles to be advanced and another bottle to be placed in position to be ejected upon the next movement of the arm.

After the bottle is placed upon the support 120 51 and the elements 67 and 104 are at rest, an intermittent step of rotation is imparted to the member 18 and the bottle supports 51 in the direction indicated by the arrow in Figure 1. During the intermittent rotation of 125 the bottle supports 51 they will be raised through the medium of the cam track 59 so that the filling mechanism will be inserted in the bottles and the filling mechanism, together with the container 23 will rotate with 130

the bottles until the bottles are brought into a position to be engaged by the arms 105 of the element 104.

During this filling operation it will be manifest that the bottles will remain closed by the filling mechanisms. As the bottles approach the element 104 they will be lowered from the filling mechanism, and if the member 61 is employed it will assist in the lowering of the bottle support. The filling mechanism will disengage the reciprocating bottles when the bottle support 51 has reached its lowermost movement, and upon the next step of rotation of the bottle supports 51 the foremost filled bottle will be engaged by the arm 105 of the member 104 to be moved from the bottle support 51 and upon the yieldable support 120 and in a position to be operated upon by the capping mechanism 106.

When released by the capping mechanism the arm 105, which remains in engagement with the bottle during the capping, will upon the next step of intermittent rotation of the element 104 remove the bottle from the capping station and place the same upon the conveyor 65 to be conveyed away.

With this improved construction it will be manifest that in the event it is desired to remove any of the bottles from the machine, such as damaged bottles, and particularly after the bottles have begun to be filled, the bottle supports 51 being yieldably held up, may be readily depressed to permit such removal of the bottle without interfering with the operation of the other bottles and mechanism and without necessitating the stopping of the machine, and without wasting the milk.

While the preferred form of the invention has been herein shown and described it is to be understood that various changes may be made in the details of construction and in the combination and arrangement of the several parts, within the scope of the claims, without departing from the spirit of this invention.

What is claimed as new is:—

1. A machine of the character described including an intermittently rotative bottle support, intermittently rotative means for delivering a bottle directly to and positioning the same upon the support, and intermittently rotative means for removing the bottle from the support, both of the said means operating simultaneously and alternately with respect to the intermittent movement of the bottle support and shaped to constitute the sole positioning means for the bottle.

2. A machine of the character described including an intermittently rotative bottle support, intermittently rotative means for delivering bottles directly to and positioning the same upon the support, and intermittently rotative means for removing the bottles from the support, the said means being disposed in close proximity to each other and simultaneously rotating in opposite directions, the said

means and the said bottle support operating alternately with respect to each other.

3. A machine of the character described including a continuously operating conveyor, filling mechanism, an intermittently movable bottle support, intermittently operating mechanism intermediate the conveyor and support, and means for successively ejecting the bottles from the conveyor and for placing them in a position to be engaged and delivered by the said mechanism directly upon the said support, the last said mechanism and support rotating in opposite directions to and alternately with respect to each other, the last said mechanism also operating upon the bottles while upon the support to centralize them with respect to the filling mechanism.

4. A machine of the character described including a plurality of continuously operating conveyors, an intermittently movable bottle support intermediate the conveyors, intermittently operating means intermediate the support and one of the conveyors for delivering the bottles from the last said conveyor and positioning the same upon the support, and intermittently operating means between the support and the other of the conveyors for delivering the bottle from the support to the last said conveyor, both of the said means operating in unison and alternately with respect to the said support and each shaped to constitute the sole means for respectively positioning the bottles.

5. A machine of the character described including a plurality of continuously operating conveyors, an intermittently movable bottle support intermediate the conveyors, intermittently operating means intermediate the support and one of the conveyors for delivering the bottles from the last said conveyor to the support and shaped to constitute the sole means for positioning the bottle upon the support, and intermittently operating means between the support and the other of the conveyors for delivering the bottle from the support to the last said conveyor, the said means operating simultaneously and in opposition to each other, the said means and the said support operating alternately with respect to each other.

6. A machine of the character described including an intermittently movable bottle support, an intermittently rotative interchangeable bottle handling element for delivering the bottles to the support, an intermittently and interchangeably mounted rotative element for removing the bottles from the support, said elements simultaneously operating and in opposite directions to each other, the said elements and the bottle support being operable alternately with respect to each other, the said elements constituting the sole means for positioning the bottle upon the support.

7. A filling and capping machine including

filling and capping mechanism, an intermittently movable bottle support, an intermittently rotative interchangeable bottle handling element for delivering the bottles to the support, an intermittently rotative interchangeable element for removing the bottles from the support, said elements simultaneously operating and in opposition to each other, the said elements and the bottle support being operable alternately with respect to each other, the first recited element constituting the sole means to centralize the bottles on the support with respect to the filling mechanism and the second recited element being shaped to assist in holding the bottle during the capping operation.

8. A machine of the character described including an intermittently rotative bottle support, a continuously operating conveyor, an intermittently rotative bottle handling element intermediate the support and conveyor, a stationary support, filling mechanism, means operating to successively eject the bottles from the conveyor to the stationary support and into a position to be placed and centralized solely by the said element upon the support and with respect to the filling mechanism, said ejecting means operating to arrest the advancing movement of the bottles by the conveyor, and an intermittently rotative element for removing the bottles from the support, the said elements operating simultaneously and in opposite directions to each other, the said elements and the said support operating alternately.

9. A filling and capping machine including filling and capping mechanism, an intermittently rotative bottle support, an intermittently rotative bottle handling element for receiving and placing the bottles upon the support and constituting the sole means for centralizing them upon the support with respect to the filling mechanism, and an intermittently rotative element for removing the bottle from the support and directly from the filling mechanism to the capping mechanism, the last recited element being shaped to assist in holding the bottle during the capping operation.

10. A filling and capping machine including filling and capping mechanism, an intermittently rotative bottle support, an intermittently rotative bottle handling element for receiving and placing the bottles upon the support and constituting the sole means for centralizing them upon the support with respect to the filling mechanism, an intermittently rotative element for removing the bottle from the support and directly from the filling mechanism to the capping mechanism, and a conveyor for conveying away the capped bottle, the last recited element also operating to move the capped bottle directly from the capping mechanism on to the conveyor.

11. A filling machine including a continuously operating conveyor for the bottles, an

intermittently rotative bottle support, an intermittently rotative bottle handling element intermediate the conveyor and support, a resilient ejector for successively removing the bottles from the conveyor and placing them into the path of movement of the said element to be engaged thereby, said element and support being alternately movable, said element also being shaped to constitute the sole means for centralizing the bottle upon the support with respect to the filling mechanism.

12. A filling machine including a continuously operating conveyor for the bottles, an intermittently rotative bottle support, an intermittently rotative bottle handling element intermediate the conveyor and support, said element being removable and interchangeable with other elements for handling different sized articles and while the remaining parts of the feeding mechanism remain intact, a resilient ejector for successively removing the bottles from the conveyor and placing them into the path of movement of the said element to be engaged thereby, said element and support being alternately movable, said element also being shaped to constitute the sole means to centralize the bottle upon the support with respect to the filling mechanism.

13. A filling machine including a continuously operating conveyor for the bottles, an intermittently rotative bottle support, an intermittently rotative bottle handling element intermediate the conveyor and support, an ejector for successively ejecting the bottles from the conveyor and into a position to be engaged by the said element, the latter being shaped to constitute the sole means for centralizing the bottles upon the said support with respect to the filling mechanism, said element and support being alternately operating, and means permitting said ejector to yield under abnormal conditions.

14. A filling machine including a continuously operating conveyor for the bottles, an intermittently rotative bottle support, an intermittently rotative bottle handling element intermediate the conveyor and support, means adapting said element for interchange with additional elements while the remaining parts of the feeding mechanism remain intact, whereby different size bottles may be handled by the machine, an ejector for ejecting the bottles from the conveyor and into a position to be engaged by the said element, said element being shaped to constitute the sole means for centralizing the bottles upon the said support with respect to the filling mechanism, said element and support being alternately operating, and means permitting the ejector to yield under abnormal conditions.

15. A machine of the character described including filling mechanism, an intermittently rotatable bottle carrier and support, capping mechanism adjacent the path of movement of the support, a stationary support be-

neath the capping mechanism, intermittently rotatable elements for respectively feeding the bottles to and from the rotatable support, one of the said elements constituting the sole 5 means for removing the bottle from the rotatable support and for centralizing the bottle upon the said stationary support with respect to the said capping mechanism.

16. A machine of the character described 10 including filling mechanism, an intermittently rotatable bottle carrier and support, capping mechanism adjacent the path of movement of the support, a stationary support beneath the capping mechanism, intermittently

rotatable elements for respectively feeding the 15 bottles to and from the rotatable support, one of the said elements constituting the sole means for removing the bottle from the rotatable support and for centralizing the bottle upon the said stationary support with respect 20 to the said capping mechanism and for holding the last said bottle during the capping operation.

In testimony whereof I have signed my name to this specification, on this 16th day of 25 April, A. D. 1925.

MAURICE GOLDBERGER.
